UNITED STATES PATENT OFFICE

131,706

DESIGN FOR A TWIN CYLINDER V-TYPE ENGINE

Henry Schreck, Beloit, Wis., assignor to Fair-
banks, Morse & Co., Chicago, Ill., a corporation
of Illinois

Application July 29, 1940, Serial No. 03,997

Term of patent 14 years

To all whom it may concern:

Be it known that I, Henry Schreck, a citizen of the United States, residing in the city of Beloit, county of Rock, State of Wisconsin, have invented a new, original, and ornamental Design for a Twin Cylinder V-Type Engine, of which the following is a specification, reference being had to the accompanying drawings, forming a part thereof.

In the drawings: Fig. 1 is an elevational view of the engine as seen from the rear or fly wheel end

thereof; Fig. 2 is a side elevational view of the engine viewed from the right side of the engine of Fig. 1; Fig. 3 is a front or forward end elevational view of the engine; Fig. 4 is a side elevational view of the engine as seen from the left side of the engine appearing in Fig. 1, and Fig. 5 is a top plan view of the engine.

I claim:

The ornamental design for a twin cylinder V-type engine, substantially as shown.

HENRY SCHRECK.
